DISPLAY CONTAINER

Paul Roberts, Sandusky, Ohio, assignor to The
Hinde & Dauch Paper Company, Sandusky,
Ohio, a corporation of Ohio

Application July 21, 1937, Serial No. 154,858

3 Claims. (Cl. 206—44)

This invention relates to a package which is particularly adapted for the combined purposes of shipping and of sales display of goods in small retail packages. In certain aspects it is particularly adapted for the transportation and sales display of oleomargarine and provides special arrangements for the printing of labels in such a manner as to be protected during transit and handling and exposed in the position and arrangement required by law in connection with retain packages during display for sales.

The box further is so proportioned and shipped as to permit an attractive display of the contained packages and to utilize them for the purpose of holding the parts of the carton in display position.

To the accomplishment of the foregoing and related ends, said invention, then, consists of the means hereinafter fully described and particularly pointed out in the claims, the annexed drawing and the following description setting forth in detail certain structure embodying the invention, such disclosed means constituting, however, but one of various structural forms in which the principle of the invention may be used.

In said annexed drawing:

Fig. 1 is a perspective view of the carton closed and sealed ready for storage or shipping;

Fig. 2 is a perspective of the carton and contents in display position;

Fig. 3 is a perspective on a smaller scale showing the carton in an intermediate position to illustrate the method of setting up for display, also showing the contents still in shipping position;

Fig. 4 is a partial vertical section on the plane 4—4 of Fig. 1; and

Fig. 5 is an end view of a modified form of box open for display.

This box comprises a bottom of conventional construction such as two outer flaps 1 and 2 overlapping two inner flaps 3 and 4, the outer flaps being hinged respectively to front 5 and back 6 and the inner flaps being hinged respectively to sides 7 and 8. Thus the box can have the top closed while empty and be packed inverted and sealed by a tape such as 10, or in any other satisfactory manner. The top 12 is a single piece hinged along the back as at 13A and attached to the sides 7, 8 by triangular wings 13, 14 and 13', 14' which hinge to the top at the lines 15, 15' and at the bottom to the line 16, 16' and each of which has a median fold line 17, 17' respectively, permitting the

panel to move inward when the lid 12 is lowered, so that the wings then underlie the lid in the dotted line positions of Fig. 1, the fold being shown in more detail in Fig. 4.

To give large exposure, the box front is divided horizontally across the middle at line 18 into the fixed lower panel 5 and movable upper panel 19. The ends of the panel 19 are cut entirely away from the sides 7, 8 respectively. A flap 20 is horizontally hinged to the panel 19, 10 along the fold line 21. When the box is closed this panel 20 overlaps the top, overlying the front half of the lid 12 and extending to about the middle of the top of the box, where it may be secured by an adhesive tape 22, or in other 15 suitable manner.

The carton is preferably made from a unitary blank of double face corrugated board as usual in this art and the side and end walls are permanently connected along a vertical edge by an adhesive tape 23 or other customary suitable means.

When the box is opened, the panel 19 is turned down 180° along the line 18, against the front 5, and the flap 20 is then turned back 180° along 25 the line 21 so that it fits completely under the carton, as shown in Fig. 2, thus uncovering the upper half of the front and also maintaining the inner surface 19A of the upper panel 19 in display position.

In this manner, the interior surface 19A and the interior surface 12A can be printed with such advertising or identifying matter as may be wished, or with adhesive tax stamps and the like and this printing or other material required to be exposed when the contents of the package is on sale can be of such a nature as to comply with the requirements of statutes and regulations with respect to the selling of oleomargarine from labeled packages. At the same time all the 40 printing or other matter to be displayed during sale is entirely protected when the box is in transit or in storage, but it is impossible to set the box up as a retail package without making the proper display.

The height of the box, when adapted for display purposes, is an integral multiple of the height of the small packages to be contained therein, and the front opening is also designed to show the ends of an integral number of contained small packages. For example in Fig. 2 the packages 30 illustrated are retail quarter-pounds of oleomargarine of standard shape, wrapped in waxed paper. The box is so dimensioned as to be exactly filled by sixty-four such 50 55

packages arranged in four stacked front layers and four stacked rear layers of eight packages each, as shown. It will be appreciated that these sizes and figures are illustrative of the principle and subject to modification.

When the box is set up for display, the top layer of the front pile is removed and piled on the top layer of the rear pile, thus displaying the ends of two layers of packages in the back pile 10 and one in the front pile, and at the same time holding the wings unfolded and the display lid back and open, exposing the inner surface 12A of the lid 12 in a position to form a background immediately above the goods and fully visible 15 to customers.

In the form of carton shown open and in left end elevation in Fig. 5, the panels are cut with a concave arcuate edge 31 as shown, but are otherwise similar to the showing in Fig. 2. Fig. 5 20 illustrates the left end and the various parts are the same as on the left end of Fig. 2 except that the letter "A" has been added to the respective reference characters. Thus the carton end is 7A, the lower wing portion 14A is hinged to 7A along 25 the line 16A, the upper wing portion 13A is hinged to 14A along the diagonal line 17A and is hinged to the back along the line 13A.

From the foregoing it will be seen that I have invented a carton in which the dimensions of 30 parts and sizes of the openings are proportioned to sizes of retail packages to be contained therein, the goods are attractively arranged for display in conjunction with portions of the carton which are protected when closed and exposed adjacent 35 the merchandise when opened, and of such a nature and arrangement that it is impossible to set up the box on a counter without making the proper exposure both of the merchandise itself and of the printed matter, and furthermore, the 40 merchandise assists in maintaining the display panels in open position.

Other modes of applying the principle of my invention may be employed instead of the one explained, change being made as regards the 45 structure herein disclosed, provided the means stated by any of the following claims or the equivalent of such stated means be employed.

I therefore particularly point out and distinctly claim as my invention:

50 1. A combined packing and display container comprising in combination side walls and a back all of which are permanently flat and of equal height, a multi-section front, a top full lap, a top part lap, and side wings each hinged to the upper 55 edge of a respective side wall, said top full lap

being hinged to the upper edge of the carton back and also having one of said side wings hinged to each end, said side wings being bendable intermediate their said respective hinge connections, said top part lap being hinged to that carton edge which is the upper front when closed, and the upper section of said carton front being hinged parallel to said edge at half the carton height and severed from the side walls above such median hinge line thereby adapting said upper 10 section to be bent 180° around said median hinge line, and the connection between said part lap and said upper section being adapted for bending 180° to form a right angle in either of two directions with said panel.

2. A combined packing and display container comprising in combination side walls and a back all of which are permanently flat and of equal height, a multi-section front, two top laps, and side wings each hinged to the upper edge of a 20 respective side wall, one of said top laps being hinged to the upper edge of the carton back and also having one of said side wings hinged to each end, said side wings being bendable intermediate their said respective hinge connections, one of 25 said top laps being hinged to that carton edge which is the upper front when closed, and the upper section of said carton front being hinged parallel to said edge at half the carton height and severed from the side walls above such median 30 hinge line thereby adapting said upper section to be bent 180° around said median hinge line, and the connection between said upper section and its connected top lap being adapted for bending 180° to form a right angle in either of two directions 35 with said panel.

3. A combined packing and display container comprising in combination side walls and a back all of which are permanently flat and of equal height, and a front of variable height, a plurality 40 of top laps one of which is hinged to the upper edge of said back respectively, two top collapsible wings each hinged to an edge of the back top lap and to a side wall top edge, and adapted to stand substantially in the planes of their respective side 45 walls in display set-up, a hinge line across said container front parallel to top and bottom at mid height and severance lines between said front and sides from top to said hinge line thereby setting off the upper section of said front as a movable 50 panel adapted selectively to close or open the container front and in either position to be vertically disposed.
